UNITED STATES PATENT OFFICE

170,681

SPORT SHIRT

Ray S. Dougherty, Kittanning, Pa.

Application July 1, 1953, Serial No. 25,747

Term of patent 7 years

(Cl. D3—25)

To all whom it may concern:

Be it known that I, Ray S. Dougherty, a citizen of the United States, residing at Kittanning, in the county of Armstrong and State of Pennsylvania, have invented a new, original, and ornamental Design for a Sport Shirt, of which the following is a specification, reference being had to the accompanying drawing, forming part thereof.

I claim:

The ornamental design for a sport shirt, as shown.

RAY S. DOUGHERTY.
